United States Patent Office

Des. 182,437
Patented Apr. 1, 1958

182,437

BOX

John Ragosta, Providence, R. I., assignor to Diamond
Paper Box Company, Providence, R. I., a corporation of Rhode Island

Application April 29, 1957, Serial No. 45,921

Term of patent 14 years

(Cl. D58—12)

Fig. 1

Fig. 2

Fig. 4

Fig. 1 is a front perspective view of a box embodying my new design;

Fig. 2 is a top view thereof;

Fig. 3 is a rear elevational view thereof; and

Fig. 4 is a side perspective view thereof.

I claim:

The ornamental design for a box, substantially as shown.
